COMBINED ELECTRIC MOTOR AND BASE THEREFOR

Charles H. Crouse and Timothy W. Hennessey, both of
Springfield, Ohio, assignors to Robbins & Myers, Inc.,
Springfield, Ohio, a corporation of Ohio

Filed Feb. 27, 1964, Ser. No. 78,798

Term of patent 3½ years

(Cl. D26—5)

FIG-1

FIG-2

FIG-3

FIG-4

FIG-5

FIGURE 1 is a perspective view of a combined electric motor and base therefor showing our new design.

FIGURE 2 is a perspective view taken from the side opposite that shown in FIGURE 1.

FIGURE 3 is a top plan view.

FIGURE 4 is an end view taken from the right hand end of FIGURE 3.

FIGURE 5 is an end view taken from the left hand end of FIGURE 3.

We claim:

The ornamental design for a combined electric motor and base therefor, substantially as shown.
